UNITED STATES PATENT OFFICE

2,095,100

TUNING CONTROL MEANS

Louis Maillard, Paris, France, assignor to General Electric Company, a corporation of New York

Application December 3, 1935, Serial No. 52,683
In France December 21, 1934

3 Claims. (Cl. 74—10)

My invention relates to a tuning control means for radio transmitting or receiving systems.

It is often desirable to turn the tuning control member of a radio transmitting or receiving system rapidly from one predetermined position to another and still have it quickly and accurately stop at a predetermined desired setting. It is an object of my invention to provide an improved tuning device which will permit a rapid and accurate change from one tuning position to another.

In accordance with my invention, the control shaft of the apparatus to be controlled carries a hollow cylindrical drum within which several rings are placed, each ring of which is provided with one or more recesses or detents. These detents co-operate with a corresponding number of balls of plungers that are carried by a stationary member mounted on the front panel of the apparatus. Each time the control shaft is moved from one desired position to another, one of the balls engages in the corresponding detent and holds the control shaft in an interlocked position. The cylindrical drum may be connected in any appropriate manner to a control handle within reach of the operator's hand.

The novel features which I believe to be characteristic of my invention are set forth with particularity in the appended claims. My invention itself, however, both as to its organization and method of operation, together with further objects and advantages thereof may best be understood by reference to the following description taken in connection with the accompanying drawing in which Figs. 1 and 2 are views partly in cross section of one embodiment of my invention.

Referring to Fig. 1 of the drawing, it will be seen that control shaft 1, whose angular position is varied according to the frequency desired, has mounted thereon a cylindrical drum 2 having an end wall 3 and a hub 4. Rotatably carried on the inner surface 5 of drum 2 are two rings 6 and 7 which are each provided with a notch or detent 8 and 9 (shown in Fig. 2) respectively on their inner peripheries. A guard ring 29 secured to drum 2 by screws 30 prevents any axial movement of rings 6 and 7. A stationary member 10 mounted on the front panel 11 of the apparatus by means of bolts 12 and 13 (Fig. 2), extends within the drum 2 between hub 4 and rings 6 and 7. Balls 14 and 15 carried in cylindrical apertures 16 and 17 of the locking member 10 are pressed against rings 6 and 7 respectively by means of springs 18 and 19. It is

apparent that when one of the rings is so turned that its detent will be opposite one of the spring-pressed balls that the ball will be forced into the detent and will then hold the ring in position.

Rings 6 and 7 may be made to coact with drum 2 by tightening set-screws 20 and 21. The position of drum 2 may be controlled by any suitable mechanism such as by providing a wheel 22 mounted on the end wall 3 by means of bolts 23 and by connecting this wheel through a Bowden cable 24 (Fig. 2) to a second wheel 25 which is rotated by means of the operating handle 26. An end cap 27 may be provided over hub 4 and an indicating disk 28 may be mounted thereon.

The operation of the tuning control is as follows: The system is first adjusted by rotating drum 2 until ball 15, for instance, engages the corresponding detent 9 of ring 7. Set-screw 21 is then loosened and the drum is rotated until the control shaft 1 has assumed an angular position representing some desired frequency of operation of the radio transmitting or receiving system. Set-screw 21 is then tightened. By a similar operation, ring 6 is adjusted for operation of the apparatus at some second desired frequency.

Assuming now that the control shaft 1 is in such a position that ball 14 rests in detent 8 and it is desired to change the frequency of operation to one determined by the position of detent 9, the operator rotates handle 26 in a counter-clockwise direction until the spring-pressed ball 15 drops into its corresponding detent 9. The system is now turned to the second desired frequency.

It is obvious that any number of rings and corresponding spring-pressed balls may be used depending, of course, upon the number of predetermined desired frequencies at which the system is intended to be operated. It is also apparent that there is no limitation as to how close together any two desired frequencies may be for one ball may just be beginning to ride out of its corresponding detent as a second ball falls into its corresponding detent.

While I have shown a particular embodiment of my invention it will, of course, be understood that I do not wish to be limited thereto since different modifications may be made, and I therefore contemplate by the appended claims to cover all such modifications as fall within the true spirit and scope of my invention.

What I claim as new and desired to secure by Letters Patent of the United States is:

1. In a control device, the combination comprising a control shaft, a plurality of rings of

substantially equal diameters disposed about said shaft, means for adjustably securing said rings to said shaft, a corresponding number of spring-pressed non-rotational elements abutting the inner peripheries of said rings, each of said rings having a detent on its inner periphery adapted to seat one of said spring-pressed elements at a predetermined angular position of said shaft.

2. In a control device, the combination comprising a control shaft, a hollow drum mounted on said shaft, a plurality of rings each having a detent on its periphery rotatably mounted within said drum, means for retaining said rings in fixed angular relation with respect to said drum, each ring being so positioned as to have its detent correspond to a predetermined desired angular position of said shaft, a stationary member ex-

tending within said drum and in proximity to said rings, and a plurality of spring-pressed elements carried by said stationary element abutting the inner peripheries of said rings, each spring-pressed element being adapted to rest in its corresponding detent at some predetermined angular position of said shaft. 5

3. In a control device, the combination comprising a stationary member, a control shaft supported thereby, a hollow drum mounted on said shaft, a plurality of rings disposed axially of said shaft and within said drum, said rings being adjustably secured to said drum and in proximity to said stationary member, and means for interlocking said shaft to said stationary member 10 through one of said rings. 15
